INK MARKING INSTRUMENT

Samuel Ayres, Jr., Marblehead, Mass., assignor to The Carter's Ink Company, Cambridge, Mass., a corporation of Massachusetts

Continuation of abandoned application Ser. No. 59,400, Feb. 15, 1960. This application Mar. 13, 1961, Ser. No. 64,317

Term of patent 14 years

(Cl. D74—17)

FIG. 1

FIG. 2

FIG. 1 is a side elevational view of an ink marking instrument, showing my new design;

FIG. 2 is a bottom plan view;

FIG. 3 is a top plan view of the cap portion; and
FIG. 4 is an exploded elevational view thereof.

The essential features of my design reside in the portions shown in solid lines on the drawings. The conventional felt nib portion has been omitted for convenience of illustration.

This application is a continuation of my copending application, Serial No. D. 59,400, filed February 15, 1960, and now abandoned.

I claim:

The ornamental design for an ink marking instrument, substantially as shown and described.
